Primary Examiner — John Windmuller*Assistant Examiner* — Steven J Czyz(74) *Attorney, Agent, or Firm* — Schroeder & Siegfried, P.A.(57) **CLAIM**

The ornamental design for an article holding stand, as shown and described.

DESCRIPTION

FIG. 1 is a perspective view of an article holding stand showing my new design;

FIG. 2 is a front elevational view;

FIG. 3 is a rear elevational view;

FIG. 4 is a right side elevational view;

FIG. 5 is a left side elevational view;

FIG. 6 is a bottom plan view;

FIG. 7 is a top plan view; and,

FIG. 8 is a perspective view with a planting container shown in broken lines.

The broken lines in the drawings represent environmental structure and form no part of the claimed design.

1 Claim, 8 Drawing Sheets(56)
